UNITED STATES PATENT OFFICE.

ARTHUR QUINTON WALSH, OF NEW YORK, N. Y.

RECEPTACLE FOR CIGARETTES.

SPECIFICATION forming part of Letters Patent No. 783,848, dated February 28, 1905.

Application filed December 16, 1904. Serial No. 237,168.

To all whom it may concern:

Be it known that I, ARTHUR QUINTON WALSH, a subject of the King of Great Britain, and a resident of the city of New York, borough of Manhattan, in the county and State of New York, have invented a new and Improved Receptacle for Cigarettes, of which the following is a full, clear, and exact description.

10 The purpose of the invention is to provide a receptacle especially adapted as a receiver for cigarettes and to so construct the receptacle that ready access may be gained to even the last cigarette therein and so that the cigarettes will be kept moist in a manner which will not affect their color or flavor.

The invention consists in the novel construction and combination of the several parts, as will be hereinafter fully set forth, 20 and pointed out in the claim.

Reference is to be had to the accompanying drawings, forming a part of this specification, in which similar characters of reference indicate corresponding parts in both figures.

25 Figure 1 is a perspective view of the improved receptacle, the rack for the cigarettes and the vessel adapted to contain moisture-distributing material being removed from the body of the receptacle; and Fig. 2 is a longitudinal vertical section through the complete device.

A represents the body of the receptacle, which is usually made mainly of glass, although other material may be employed, and 35 when the said body is made of glass a metal binding 10 is provided at the upper marginal portion of the body, and to this binding at one side of the box-body a cover 11 is hinged in any approved manner. This cover is also 40 preferably of metal.

B represents a vessel adapted to contain the moisture-distributing material. This vessel B is made, preferably, of metal and is adapted to fit into the box-body A and is designed to 45 occupy a central position therein. The vessel B is constructed with a closed bottom and open top and has fenestrated side and end portions. Ordinarily when the vessel B is in

the box-body A the top of the vessel is practically flush with the upper edge of the said 50 box-body.

C represents a rack on which the cigarettes are placed, and the said rack likewise serves to hold the vessel B in its central position within the box-body A, and the said rack C 55 consists of parallel bars 12, which bars 12 are secured to the bottom of the vessel B and are of sufficient length to extend from end to end of the box-body A, so that when the receptacle B is removed or lifted it carries the 60 rack C with it.

Preferably a lemon is placed in the vessel B, as in practice it has been found that the oil contained in the rind of the lemon suffices to keep the tobacco or cigarettes moist and 65 does not injure the flavor of the tobacco. Furthermore, if but few cigarettes remain in the receptacle they may be conveniently reached by simply lifting up the vessel B, whereupon the cigarettes will be carried up 70 with it by engagement with the members of the rack C, enabling a person to have ready access to even the very last cigarette in the box. However, I do not restrict myself to any particular way of packing the cigarettes 75 in the receptacle.

Having thus described my invention, I claim as new and desire to secure by Letters Patent—

A receptacle for cigarettes consisting of 80 a box-body, a cover therefor, a vessel adapted to be removably placed in the said box-body, which vessel is provided with fenestrated sides and ends, an open top and a closed bottom, and a rack carried by the said vessel, which 85 rack consists of parallel bars secured to the bottom of the vessel and extending beyond its ends, the ends of said bars when said vessel is placed in said box-body being close to the ends of the box-body, for the purpose specified.

In testimony whereof I have signed my name 90 to this specification in the presence of two subscribing witnesses.

ARTHUR QUINTON WALSH.
